MACHINE FOR STATISTICAL COMPUTATIONS

Martin Rosenberg, Brooklyn, and Matthew Cohen, now by judicial change of name Matthew Conrad, Jamaica, N. Y.

Application June 2, 1943, Serial No. 489,586

5 Claims. (Cl. 235—61.6)

Our invention relates particularly to a machine whereby statistical data may be readily ascertained from a plurality of records thereof. This is accomplished preferably by utilizing light transparent areas on a record of any desired character, such for instance as a motion picture film, each frame of which can represent a punched card or a portion of a punched card in a Hollerith counting system.

The object of our invention is to provide a machine of this character by which statistical data may be obtained from a succession of individual records containing data of any desired character. A further object is to provide a machine of this kind which is operated from a motion picture film carrying a series of frames, each of which contains records of data to be compiled by means of the machine. Another object is to actuate the statistical mechanism of the machine by the position of light transmitting areas in the film the object being, furthermore, to maintain the synchronism in the operation of the machine, not only for successive frames of data recorded on the film but also in the successive lines of data recorded on the film and by means of which self-synchronization is obtained. Still another object is to carry out scanning by means of an electron beam, preferably in a cathode ray tube. One of the objects is, furthermore, to scan each particular frame of the film while at rest, only one photo-electric cell being needed therein. Still another object is to provide advantageous circuit arrangements for controlling the movement of the said beam. Our apparatus is of the type in which the value of a particular integer or digit is determined by a sweep horizontally while the places or denomination of the particular numbers are determined by differences in relative positions vertically. Further objects of our invention will appear from the detailed description of the same hereinafter.

While our invention is capable of embodiment in many different forms, for the purpose of illustration we have shown only one form thereof in the accompanying drawings, in which—

Figs. 1 and 1A are a diagrammatic representation of an apparatus made in accordance with our invention;

Fig. 2 is an elevation of a portion of a motion picture film which may be used in connection with our apparatus; and

Fig. 3 is a section on line 3—3 of Fig. 1A.

In the drawings, we have shown a cathode ray tube 1 which may be of any known or usual construction, but which, for example, is shown as a

cathode ray tube designed for electrostatic deflection of the electron beam produced therein. For this purpose the cathode ray tube 1 comprises the usual glass tube 2 having a conical end 3 provided with a circular light emitting surface 4 in the form of a fluorescent coating on the interior of the tube 2. The tube 2 contains in the usual way a rarified atmosphere and a beam of electrons is produced therein from a filament 5 located in a circuit 6 having a source of current 7 for this purpose. Within the tube 2 there is a metal cylinder 8 surrounding the path of the beam of electrons in order to accelerate and focus the same into a narrow electronic beam 9, the cylinder 8 being adapted to receive an electrostatic charge from a wire 10 connected to a source of current 11, which in turn is connected by a wire 12 to the circuit 6. The electronic beam 9 is arranged to be deflected substantially horizontally by plates 11a and 12a within the tube 1, and which are provided with varying voltage potentials from amplifier output wires 13 and 14 leading, respectively, to an amplifier 15 constructed in any desired or usual way, it being understood that the electrons of the beam 9 are deflected towards one of the plates 11a and 12a having a relatively positive potential thereon at any given moment. The amplifier 15 is connected to input wires 16 and 17. Furthermore, the said cathode ray tube has therein opposed plates 18 and 19 for the vertical deflection of the electronic beam 9, the same being connected, respectively, by wires 20 and 21 to an amplifier 22 constructed in any desired or usual way, and which has connected thereto input wires 23 and 24.

The electronic beam 9, which is accelerated and focused by the cylinder 8 impinges on the fluorescent screen 4 in the usual way, the light emitted by the screen 4 being passed through an aperture 25 in a conical housing 26 having a lens 27 to concentrate the light onto a photoelectric light sensitive cell 28 constructed in any desired or usual way, but which may, for example, have an alkali metal cathode surface 29 therein, such, for example, as sodium or caesium, preferably in a high vacuum tube 29c, the resistance of which varies with the intensity of the light received thereby. The surface 29 is connected by input wires 30 and 31 to an amplifier 32 constructed in any desired or usual way, which in turn is connected to output wires 33 and 34 in a circuit, one end of the wire 34 being connected to a ground 35 while the other wire 33 is connected to a brush 36 on a rotary commutator hub 37

carrying fixedly thereon a conducting arm 38 which is rotatable on a commutator 39. The commutator 39 has a non-conducting space 40 and conducting areas 41, 42, 43, 44, 45, 46, 47, 48, 49 and 50. The areas 41 to 50 correspond, respectively, to the ten lines of data in each frame on a motion picture film 51, which is carried on a supply reel 52 feeding the film in the direction of the arrows to a reel 53 on which the film is to be rolled up. As shown in Fig. 2, the film has the usual sprocket holes 54 for advancing the film intermittently by means of fingers 55 on a rotary hub 56. The said film, furthermore, has a series of light transparent areas 57, 58 etc., one for each frame, for synchronizing the respective frames of data with the apparatus. As shown in Fig. 2, ten or any other desired number of lines of light transparent areas or holes 59 are carried by the film to be scanned. A mask 60 masks out the lines opposite the light transparent areas 57, 58 etc., and is not attached to the film but is rigidly supported so as not to move relative to the cathode ray tube. The film also carries a vertical light transparent strip 61 for synchronizing the respective ten lines of data. Guide rolls 62 and 63 guide the film 51 in the usual way between the circular area 4 on the tube 1 and the housing 26. Between the conducting space 50 and the non-conducting line 40 there is a conducting terminal 64 on the commutator 39 for operation with each of the light transparent areas 57, 58 etc. to synchronize the successive frames of data. Also, between the non-conducting space 40 and the respective conducting lines 41 to 50 there are conducting terminals 65, 66, 67, 68, 69, 70, 71, 72, 73, 74 and 75 for synchronizing the ten lines of data on the film with the apparatus. In addition, connected to the successive conducting lines 41 to 50 there are one or more conducting terminals 76, 77, and 78 at the lines 43, 44 and 45, and of the same kind at the remaining terminals 41, 42, 46, 47, 48, 49 and 50 (not shown), for operating accumulating and tabulating number wheels 80, 81 and 82 and, if desired, additional number wheels (not shown), shown diagrammatically herein as a part of any desired adding or tabulating or accumulating machine, such, for example, as shown in the patent to Lake, No. 1,534,531 (which refers to the patent to Hollerith No. 945,236), granted April 21, 1925, or Bryce, No. 2,124,906, granted July 26, 1938, it being understood that the wheels, after accumulation of the data therefrom, may be reset by hand or as disclosed in the patents to Lake or Bryce.

At the starting position of the apparatus the conducting arm 38 will be over the terminal 64, which point has been reached after the accumulation of the data of one of the frames on the film 51, and in this position a circuit will have been made by the arm through the terminal 64 and a wire 81a connected thereto leading to a trigger magnet 82a which releases a catch 83 carried by a pivot 84 normally moved into engagement by a spring 85 with a cam stop 86 on a shaft 87 so that when the circuit is made through the wire 81a the catch 83, which has been used to bring the entire moving system to rest, is released from the cam stop 86, permitting the rotation of a belt 88 on a pulley 89 located on the shaft 87 and which passes over a pulley 90 on a shaft 91, thus bringing the system into rotation. The pulley 90 is driven by a belt 92 passing over a pulley 93 having a friction face 94 which is adapted to be driven by a friction face 95 carried by a pulley 96 on a shaft 75

97. When the current is received from the wire 81a to release the catch 83 the circuit is completed through a wire 98 which leads to a coil 99 which is adapted to move a lever 100 on a pivot 101 operating a yoke 102 provided with a shaft 103 supporting a friction wheel 104 which, when moved by the magnet 99, makes frictional contact between the friction surfaces 94 and 95. This conveys power from a belt 105 on the pulley 96 which is driven by a pulley 106 on a shaft 107 of a continuously rotating electric motor 108 of any desired type. The coil 99 leads to a ground 109 and when the circuit has been made through the coil 99 a stick circuit 110 is completed by the coil 99 by means of a terminal 111 cooperating with a switch arm 112 normally retracted by a spring 113. By this means, once the circuit is made through the coil 99 the circuit therefrom is maintained, notwithstanding the breaking of the current in the wire 81a, until the stick circuit through the contact 111 is interrupted. The current for the stick circuit is supplied to the switch arm 112 by a wire 114 connected to a battery 115, or other source of current, which in turn is connected by a wire 116 to a terminal 117 for cooperating with a switch arm 118 adapted to be moved by a coil 119 connected to a ground 120, and which is connected to a spring switch arm 121 normally out of contact with a terminal leading to a battery 123 and a ground 124. The switch arm 121 is adapted to be made to contact with the terminal 122 by an insulating end 125 on the outer end of the conducting arm 38, just before the said arm 38 reaches the conducting terminal 64. This breaks the stick circuit 110 and disconnects the friction wheel 104 from the friction surfaces 94 and 95 ready to start the operation over again. The advancing of the film one frame is accomplished while the arm 38 is opposite the non-conducting line 40. This is accomplished by a belt 126 which passes from the pulley 90 over a pulley 127. The pulley 127, by means of band 128, drives a pulley 129 located on and free to rotate about a fixed bearing shaft 130 on which the hub 37 is rotatably mounted and rigidly connected to the pulley 129. Also, the said pulley 127, by means of a band 130a, drives a pulley 131 free to rotate about a shaft 132, said pulley 131 having attached thereto the hub 56 which is provided with the fingers 55 which cooperate with the perforations 54 on the film 51 to move the film to the next frame. This movement of the film 51 to the next frame, as above indicated, takes place in the interval represented by the non-conducting line 40. Meantime, from the point where the arm 38 has started to advance from the conducting terminal 64 the beam of light will be deflected slowly downwardly while being oscillated horizontally and will in this downward movement extend all the way to cover the ten lines of the frame in the film in one revolution of the shaft 130. During the movement of the beam corresponding to the line t, of Fig. 2, the arm 38 will move the distance 40 indicated on Fig. 1, and the beam will move the remaining distance downwardly, represented by lines B, HM, TM, M, HTh, TTh, Th, H, T and U on Fig. 2 in the remainder of the 360° of rotation of the shaft 130 represented by B, HM, TM, M, HTh, TTh, Th, H, T and U on Fig. 1. This downward deflection of the beam 9 brought about by the arm 38 contacting with the terminal 64, and receiving current due to the light beam passing through 57, 58 etc., is initiated by the wire 81a leading to a wire 133 which is connected to a grid 134 of a thyratron tube or

grid controlled ionic conduction tube 135. This tube 135 has an anode 136 connected to a source of current or battery 137 by a wire 138. The said battery 137 is also connected by a wire 139 to a switch terminal 140 cooperating with the switch arm 118. The tube 135 is provided with the usual amount of vapor or gas, for example of mercury, argon or neon. The tube 135, furthermore, has a cathode 141 which is connected to branch wires 142 and 143 provided, respectively, with resistances 144 and 145. The resistance 144 is connected by a wire 146 to an anode 147 of a tube 148 similar to the tube 135. The tube 148, furthermore, has a cathode 149 connected by a wire 150 to a ground 150a and to the resistance 145, it being understood that the resistances 144 and 145 are so adjusted as to give the desired difference of potential between the anode 147 and the cathode 149. Also, a condenser 151 is connected across the wires 146 and 150 by means of wires 152 and 153. A grid 154 in the tube 148 is connected by a wire 155 and a battery 156 to a wire 157 connected to the wire 150, which is also connected to the wire 24 leading to the input side of amplifier 22. The wire 23, connected to the amplifier 22, leads to the wire 146 and the anode 147. When contact is made by the arm 38 with the terminal 64 a potential is produced on the grid 134 which is sufficient to start the current between the anode 136 and cathode 141 which then, through the resistances 144 and 145, produces the different potentials on the anode 147 and cathode 149 so as to bring about ultimately a flow of current between the same. This difference in potential between the anode 147 and cathode 149 accumulates by reason of the condenser 151 until the point is reached where the charge on the condenser 151 is so great as to break down the tube, that is to say the current between the anode 147 and the cathode 149. During the accumulation produced by the condenser 151 the beam 9 is moving slowly downwardly over the successive lines *t* and *B*, HM, TM, M, HTh, TTh, Th, H, T and U of the particular frame of the film 51 and when the tube 148 breaks down, as above indicated, the beam is quickly moved upwardly to its original starting position. Also, during this vertical deflection of the beam 9 by the plates 18 and 19 it is being horizontally deflected back and forth all the time by the plates 11a and 12a. When the beam has moved downwardly opposite the line *B* of Fig. 2, the arm 38 will have reached the contact 65 and will thus have caused the accurate beginning of the horizontal oscillation of the beam 9 by reason of the horizontally oscillating beam having passed over or reached the vertical transparent band 61 on the film 51. Thus, when the beam has become lowered to a point opposite the line *B*, on Fig. 2, the arm 38 will have made contact with the terminal 65 and similarly thereafter in the successive lines HM, TM, M, HTh, TTh, Th, H, T and U with the contacts 66 to 75, all of which are connected together by wires 159, 160, 161, 162, 163, 164, 165, 166, 167, 168 and 169 to a wire 170 which in turn is connected by a wire 171 to a grid 172 in a tube 173 like the tubes 135 and 148. The circuit arrangement of this tube 173 is similar to the circuit arrangement of the tube 148 except that instead of having a tube such as the tube 135 for initially energizing the tube 173, the latter operates by means of current derived from a battery or source of current 174. For this purpose the tube 173 is provided with an anode 175 connected by a wire 176 to the wire 16 and to a

variable resistance 177 leading by a wire 178 to the battery 174 and connected also to a condenser 179 which is connected to the wire 17 as well as to a wire 180 leading by a wire 181 to a cathode 182 in the tube 173. The said wire 181 is also connected by a wire 183 to a terminal of the battery 174 and the said wire 183 is bridged to the grid wire 171 by means of a wire 184, a battery 185, a wire 186 having a ground 187 and a wire 188 leading to a resistance 189 which is connected by a wire 190 to the grid 172. This arrangement provides a horizontal oscillation for the beam 9 owing to the fact that the condenser 179 builds up potential by reason of the charge from the battery 174 which flows through the resistor 177. This potential is built up by the condenser 179 to the point where it finally breaks down at the gap between the anode 175 and cathode 182 so as to be started over again by the charging of the condenser 179 from the battery 174. The battery 185 serves, as in the case of the battery 156, to bias the grid 172 to a proper operating potential. When the beam reaches or passes over the transparent strip 61, however, a charge is conveyed by the wire 171 to the grid 172 sufficiently to break down the tube 173, thus returning the beam to the left-hand column of the frame, in Fig. 2, to start the accurate scanning of the lines of transparent areas or openings 59. The quick return of the beam, due to the break down of the tube 173, will cause the beam 9 to pass quickly towards the left in a substantially horizontal line so as not to encounter the openings 59 on the movement toward the left, in Fig. 2, so that when the beam is moved toward the right on the further downward deflection of the beam the latter passes over whatever areas 59 are in the particular line being scanned. It will be understood that the circuit of tube 173 is normally adjusted so that potential across the tube 173 will become sufficient to cause conduction in the tube at a time corresponding to the point where the light beam passes a short distance to the right of the transparent band 61. Thus, the tube 173 will become conducting when the light beam passes to the right of the band 61, irrespective of the grid 172.

This data indicated by the location of the transparent areas 59 on the film 51 is arranged to be transferred to a counting or tabulating machine, which is shown diagrammatically in Fig. 1A as being driven by a shaft 191 by means of a conical friction surface 192 engaging with a conical friction surface 193 on the pulley 121. The shaft 191 has splined for longitudinal movement thereon a succession of clutch elements 193, 194 and 195 which have lateral serrated faces 196, 197 and 198 for engagement with serrated faces 199, 200 and 201 on the number wheels 80, 81 and 82 carrying a succession of digits 202, 203 and 204 on the peripheries thereof. These numbers 202, 203 and 204 can be integrated into any desired compiled data according to the type of machine in which they are used, as, for example, a machine such as shown in the Lake or Bryce patents above referred to. The wheels 80, 81 and 82 are actuated by the clutch members 193, 194 and 195 being thrown into contact with the said wheels 80, 81 and 82 which are normally carried loosely by the shaft 191. The clutch members 193, 194 and 195 are thrown into action, respectively, by means of arms 205, 206 and 207 carried on pivots 208, 209 and 210, respectively, the said arms being normally with- drawn by springs 211, 212 and 213. These arms

205, 206 and 207 are moved by armatures 214, 215 and 216 of magnets 217, 218 and 219 having wires 220, 221 and 22 connected to a ground wire 223 connected by a wire 224 to a ground 225. The other ends of the magnets 217, 218 and 219 are connected by wires 226, 227 and 228 to coils 229, 230 and 231 of stick circuits comprising wires 232, 233 and 234 which lead, respectively, to terminals 235, 236 and 237 cooperating with switch arms 238, 239 and 240 carried on pivots 241, 242 and 243 and normally retracted by springs 244, 245 and 246. The switch arms 238, 239 and 240 are connected by a wire 247 to a battery 248 which has a wire 249 leading to a terminal 250 cooperating with the latch-breaking arm 118. As shown in Fig. 1, a spring 251 normally holds the switch arm 118 in contact with the terminals 117, 140 and 250. The circuit, including the wire 223, is broken when the zero digit is reached at the end of each horizontal sweep, as in the patent to Hollerith No. 945,236. For instance, this may comprise a circuit breaker 248a located in the line 223 operated by a cam 249b and may be driven by the shaft 191. Wires 252, 253 and 254 also connect the coils 229, 230 and 231, respectively, with the conducting terminals 78, 77, 76 on the commutator 39, which are, respectively, connected to the conducting areas 45, 44 and 43.

It will be noted that in the applicants' apparatus shown in the drawings, the value of the particular integer or digit is determined by the position along each particular horizontal row in Fig. 2, that is to say the numbers of the digits 9 to 1 and 0 correspond to the ten places 9, 8, 7, 6, 5, 4, 3, 2, 1, 0, one for each vertical column. The vertical letters B, HM, TM, M, HTh, TTh, Th, H, T and U in said Fig. 2 represent the places or denominational orders, respectively, in a ten place number. For example, the number in said Fig. 2 is, accordingly, 9784261530, represented by the transparent or solid line circles.

In the operation of our apparatus, the motion picture film 51, carrying a succession of frames of data registered thereon by transparent areas or perforations, is fed into the apparatus by inserting the reel 52 carrying said film therein and connecting the end of the film to the reel 53. The film is fed into the machine by turning the machine manually or otherwise until one of the transparent areas 57, 58 etc. comes opposite to the external left hand end of the path of movement of the beam of light produced by the cathode ray beam 9 impinging on the fluorescent surface 4. It is to be understood that the several batteries and amplifiers illustrated in the drawings, and the motor 108, are each provided with the usual hand switches or other means for initiating and stopping their operation. It is to be understood further that the cathode ray beam normally is set, by adjusting the normal biasing potentials applied to the deflecting plates thereof, to such a position that the extreme left hand position of the beam will be in the vertical line that is determined by the transparent areas 57 and 58 so that in the feeding of the film 51 forwardly the extreme left hand position of the beam will intersect said areas 57 and 58. Briefly, when the beam has reached one of the areas 57 and 58, the fingers 55 will move the film 51 forwardly the distance of one frame while the beam is passing towards the right, in Fig. 2, behind the stationary mask 60 and the beam thus is caused to move towards the right and then towards the left and downwardly until the whole frame is scanned. When the beam has reached the 0 position in

the bottom row or shortly thereafter the beam returns directly to the spot 57 or 58 on the same frame which has just been scanned, thus advancing the film to the next frame to be scanned. 5 The conducting arm 38, being at rest opposite the conducting terminals 64, will thereupon energize the grid 134, producing a current between the anode 136 and cathode 141, whereupon charges of different potentials, due to the resistances 144 and 145, are produced on the anode and the cathode 149. The difference in potential in the wires 153 and 152 will then accumulate in the condenser 151 until the accumulation is so great as to cause the break down of the tube 148. 10 Accordingly, during this period of accumulation in the condenser 151 the cathode ray beam 9 will move slowly downwardly under the influence of the charges on the plates 18 and 19 and the whole range of lines t and B, HM, TM, M, HTh, TTh, Th, H, T and U has been traversed and upon the break down of the tube 148 the beam will be quickly shifted upwardly to its starting position. It is to be remembered that in accordance with the well known characteristic of a tube of the 15 class of grid-controlled gaseous atmosphere tubes, as in 135, once the anode current has been initiated by a voltage energizing the grid by a positive potential, the grid "loses control" of the anode current and the latter continues irrespective of the interruption of the energizing voltage. During this downward movement of the beam 9 it will first traverse the height of the line t during which interval the beam of light is cut off from the film 51 by the mask 60. By the time the beam has reached line B, in Fig. 2, that is to say when the arm 38 has reached the contact 65, the horizontally deflected beam of light will be past the vertical transparent light strip 61 and will be quickly returned therefrom to the position at the left side of the film 51 by the break down in the tube 148 caused by the circuit connection 171 energizing the grid 172 to a sufficient extent for this purpose. This break down starts the horizontal deflection over again due to the tube 148, the said horizontal deflection being brought about by the gradual accumulation of increased potential by the condenser 179. This increase of potential on each oscillation finally breaks down the tube 148 which would take place normally 20 at or to the right of the transparent strip 61, but the break down is made to synchronize accurately with the lines of the film by energizing the grid 172 through the circuit 171 when the arm 38 reaches each of the conducting terminals 65 to 25 75 in succession and when the light beam reaches the transparent strip 61. The values of the condenser 179 and the resistor 177 are selected so that the frequency of oscillation of the vertical sweep circuit will be one tenth the frequency of the horizontal sweep circuit. It will be noted that the resistor 177 is shown in the drawings, Fig. 1A, as being a variable resistance, so that the above described frequency adjustment may readily be made. Also, when in each of the spaces 30 41 to 50—it being understood that each of said spaces can have a terminal comparable to the terminals 76 to 79—and when the beam passes over a particular one of the transparent areas 59 in the line preceding the particular one of the said terminals 76 to 79, the particular circuit 252, 253 and 254 will be energized at that point to close the particular stick circuit 232 or 233 or 234 so as to move its particular wheel 80, 81 or 82 forwardly, that is to say to advance their setting in the usual manner of a Hollerith counter,

a distance equal to the remaining number of spaces in the particular one of the lines B and U so that thereby the particular number wheel 80, 81 or 82 stops at the particular number indicated by the position of the transparent area 59 that has been so scanned. The circuit is broken and the particular clutch 193, 194 or 195 is thrown out by the breaking of the particular stick circuit owing to the circuit breakers 249a breaking the holding circuit at the end of each horizontal sweep. The numbers thus registered by the stop positions of the wheels 80, 81 and 82 will then be added, collated, compiled or otherwise registered on the particular statistical mechanism desired to be used therewith. The adding mechanism goes through one cycle (one revolution of the shaft 191) for each horizontal sweep of the scanning beam. It will be understood, thus, that when the beam of light initially passes through the transparent area 57 it causes the rotation of the arm 38 over the commutator 39 owing to the completion of the circuit through the wire 81a which releases the cam stop 86, closes the contacts 111 and 112 in the stick circuit, and moves the friction wheel 104 into contact with the friction wheels 93 and 96 so as to convey power from the continuously operated motor 108 to the pulley 127 which drives the belt 128 and thereby the arm 38. The arm 38 opposite the line t performs the function indirectly of shifting the film to the next frame by the belt 130, by the fingers 55 engaging the perforations 54 in the film 51 and during the remainder of its 360° rotation scans the ten lines of said film 51 in succession. When the arm 38 reaches the spring switch arm 121 it energizes the magnet 119 to break the circuit with all three contacts 117, 140 and 250, thus momentarily breaking the circuit through the tube 135, thereby stopping the conduction through this tube until such time as the grid 134 is energized, and all the stick circuits to start the movement of the film to the next frame and the scanning of the ten lines of the new frame. The conical friction driving elements 94, 95 and 104, 192 and 193 and the belts 128 and 130, the showing of which is merely diagrammatic as stated above, will be operated preferably at low speeds, although high speeds may be used, if desired, but are not by any means essential in the operation of the apparatus. However, it will be understood that, instead, any other type of gearing may be used for this purpose, if desired.

While we have described our invention above in detail it is to be understood that many changes may be made therein without departing from the spirit of the same.

We claim:

1. An apparatus controlled by a photographic film strip, comprising coded transparent areas, means for advancing the same to successive stationary positions, each corresponding to a frame, a device, including a cathode ray tube having cathode ray deflecting means therein, for transmitting a beam of light through portions of the stationary film successively, a photoelectric sensitive element arranged to receive the successively transmitted light beams and a registering mechanism for registering the impulses received from said photoelectric sensitive element, said deflecting means including plates adapted to carry electrostatic charges, a sweep circuit connected to a portion of the deflecting means to cause vertical deflection thereof, said film hav-

ing a light transparent area at the beginning of each frame, and means controlled by said transparent area when said light beam passes therethrough to initiate the sweeps in said sweep circuit so as to maintain synchronism between the deflection of the light beam produced by the sweep circuit and the film advancing means, a commutator, a conducting arm movable over the commutator adapted to transmit current from the photoelectric sensitive element to distribute the current from the photoelectric sensitive element to the registering mechanism in the operation of the sweep circuit by said transparent area, means to rotate the arm through one cycle while the cathode ray is being deflected throughout the length of the film frame longitudinally of the film, said advancing means being operated in timed relation to the last mentioned means, a second sweep circuit connected to the remainder of the deflecting means to cause a plurality of horizontal deflections for each vertical deflection, said film having a light transparent area to transmit light at the end of each horizontal deflection and means controlled by said conducting arm to initiate the operation of said second sweep circuit each time the light beam detects said last mentioned transparent area.

2. A machine of the type set forth in claim 1 in which the second sweep circuit has a grid and the registering mechanism has a plurality of registering means in circuit, respectively with areas on the commutator located between successive positions thereon connected to the grid of said horizontal deflecting means.

3. In a machine controlled by a photographic film strip, each frame of which has data represented thereon by light modifying marks located in denominational columns and digital rows, means for advancing said film strip, frame by frame, to successive stationary positions, a cathode ray tube for transmitting a beam of light through said film for detecting said data representing marks, said tube having two pairs of deflecting plates for causing deflection of said beam in two directions, a photoelectric means arranged to receive the light transmitted through said film as modified by said marks, each film frame being provided with a special light modifying mark, a first sweep circuit connected to one of said pairs of plates for causing deflection of said light beam in the direction of said digital rows, a distributor having an arm connected to said photoelectric means, normally operative means for operating said distributor, means controlled by said photoelectric means through said distributor for initiating operation of said sweep circuit upon detection of said special mark so as to synchronize the operation of said sweep circuit with said film advancing means, a second sweep circuit connected to the other pair of deflecting plates for causing a plurality of deflections of said light beam in the direction of said denominational columns for each deflection by the first sweep circuit, each film frame having further means for modifying the light beam at the end of each columnar deflection thereof, means controlled by said photoelectric means through said distributor for initiating a new cycle of said second sweep circuit each time the light beam is modified by said further light modifying means, a plurality of data registering devices, one for each denominational column and operable in synchronism with said distributor arm and means controlled by said photoelectric means and said distributor for causing successive operation of said registering devices as

the light beam sweeps across related denominational columns of light modifying marks.

4. In a machine controlled by a photographic film strip, each frame of which has data represented thereon by light modifying marks located in columns and rows located substantially at right angles to each other, means for advancing said film strip, frame by frame, to successive stationary positions, a cathode ray tube for transmitting a beam of light through said film for detecting said data representing marks, said tube having two pairs of deflecting plates for causing deflection of said beam in two directions, a photoelectric means arranged to receive the light transmitted through said film as modified by said marks, each film frame being provided with a special light modifying mark, a first sweep circuit connected to one of said pairs of plates for causing deflection of said light beam in the direction of said rows, a distributor having an arm connected to said photoelectric means, normally operative means for operating said distributor, means controlled by said photoelectric means through said distributor for initiating operation of said sweep circuit upon detection of said special mark so as to synchronize the operation of said sweep circuit with said film advancing means, a second sweep circuit connected to the other pair

5 of deflecting plates for causing a plurality of deflections of said light beam in the direction of said columns for each deflection by the first sweep circuit, each film frame having further means for modifying the light beam at the end of each columnar deflection thereof, means controlled by said photoelectric means through said distributor for initiating a new cycle of said second sweep circuit each time the light beam is modified by said further light modifying means, a plurality of data registering devices, one for each column and operable in synchronism with said distributor arm and means controlled by said photoelectric means and said distributor for causing successive operation of said registering devices as the light beam sweeps across related columns of light modifying marks.

10 20 25 5. A machine of the type set forth in claim 4 in which the normally operative means to operate the distributor and the data registering devices in synchronism are effective to operate the film advancing means, a clutch means for controlling the operation of said operative means and control means therefor also controlled by said photoelectric means through said distributor upon detection of said special mark.
